UNITED STATES PATENT OFFICE.

THOMAS COUSINS, OF NORWALK, CONNECTICUT.

CHILD'S TRAY.

SPECIFICATION forming part of Letters Patent No. 356,572, dated January 25, 1887.

Application filed July 22, 1886. Serial No. 208,728. (No model.)

To all whom it may concern:

Be it known that I, THOMAS COUSINS, of Norwalk, in the county of Fairfield and State of Connecticut, have invented a new and Improved Child's Tray, of which the following is a full, clear, and exact description.

My invention relates to trays for children's use, and has for its object to provide a tray wherein a plate will be retained in a fixed and protected position; also, wherein provision is made to receive a drinking-vessel, and, in the event the contents of said vessel should be spilled, wherein the fluid will be conveyed from the said tray through aperture therein to an under or subsidiary tray.

It consists in the construction of the said upper tray, and in the combination with an under or subsidiary tray, as will be hereinafter fully set forth, and pointed out in the claims.

Reference is to be had to the accompanying drawings, forming a part of this specification, in which similar letters of reference indicate corresponding parts in both the figures.

Figure 1 is a plan view of my tray together with a subsidiary tray, and Fig. 2 is a longitudinal vertical section through the line $\alpha\alpha$ of Fig. 1.

A represents a tray for the use of children at the table, adapted to enter a subsidiary tray, B, of ordinary construction. The said tray A, constructed of any suitable material, or of any desired shape, is provided with the usual bottom, a , in which a large circular opening, b , is cut at one side, nearer the outer than the inner edge thereof.

The bottom a of the tray A, in the immediate vicinity of the opening b , is struck up to form a convex or embossed surface, c , around the same. The edge of the said opening, constituting a continuation of the convexed surface c , is curved inward and downward.

The purpose of the opening b in the bottom a is to expose the receiving surface of a plate, D, placed upon the subsidiary tray B, the said plate being held firmly in position therein by means of the inwardly-curved edge of the opening b , bearing upon the same, while the embossed or convex surface c , formed around the said opening in the bottom a , accommodates the flaring sides of the plate, and serves as an additional stay therefor.

Toward the upper right-hand corner of the tray A, and usually above the center of the large opening b therein, I cause another and smaller opening, d , to be made in the bottom a , adapted to receive a glass, E, as shown, a cup or other drinking-vessel, and at intervals in the said tray-bottom a , around and about the said openings b and d , I cut therein small drain-apertures e , adapted to convey to the subsidiary or under tray, B, any milk, water, or other fluid that may be spilled upon the surface of the tray A, and thereby prevent the soiling of the children's clothes.

In the use of a tray constructed as described, the plate being held between an upper or receiving tray and an under or subsidiary one, a child, while having easy access to the contents of said plate, is unable to throw or let fall the same from the table, and the cup or glass fitting in its opening in the upper tray is not so liable to be overturned by the child, and in the event its contents are spilled the drainage-holes provided therein quickly conduct the fluid to the said under or subsidiary tray, leaving the upper or receiving tray clean and dry.

From the foregoing description, taken in connection with the drawings hereto annexed, the operation of the invention will be readily understood.

Having thus fully described my invention, I claim as new and desire to secure by Letters Patent—

1. A child's tray provided with an opening having a convexed or embossed surrounding surface and a downwardly and inwardly incined-edge, and also provided with a smaller plain edge opening, substantially as shown and described, and for the purpose herein set forth.

2. The combination, with a child's tray provided with an opening therein adapted to register with a plate beneath it, a smaller opening adapted to receive a drinking-vessel, and draining-apertures, of a subsidiary or undertray, substantially as shown and described, and for the purpose herein set forth.

THOS. COUSINS.
